UNITED STATES PATENT OFFICE.

JOHN M. MOFFATT, OF NEW YORK, AND EDWARD BLAKENEY, OF BROOKLYN, N. Y.

QUADRUPLEX TELEGRAPHY.

SPECIFICATION forming part of Letters Patent No. 351,933, dated November 2, 1886.

Application filed July 3, 1886. Serial No. 207,047. (No model.)

To all whom it may concern:

Be it known that we, JOHN M. MOFFATT and EDWARD BLAKENEY, citizens of the United States, and residents, respectively, of New York, in the county and State of New York, and of Brooklyn, in the county of Kings and State of New York, have invented certain new and useful Improvements in Quadruplex Telegraphy, of which the following is a specification.

The invention relates to the class of apparatus employed for transmitting two messages simultaneously in the same direction over a single telegraph main line, and it naturally involves the duplexing of such system also.

The object of the invention is to provide convenient and effective means for preventing the false signals which are usually manifest in the neutral relay, and caused by reversal of the polarity of the current upon the line at the distant station.

In the accompanying drawings, which illustrate the invention, Figure 1 is a diagram showing the general organization of circuits and apparatus embodying the principle of our invention, and Fig. 2 illustrates a slight modification. Fig. 3 is a modified form of inductor.

Referring to Fig. 1, L represents a telegraph main, and K² and K', respectively, represent a key for increasing the strength of currents and a pole-changing key for transmitting currents from a battery, O. One pole of this battery is connected with the lever of the key K², and when the keys are in the position shown its connections are continued through the key K' to the earth at G. The other pole is connected with the reversing key K' in a manner well understood. The battery O is divided, as shown, by a conductor leading from an intermediate point to the key K², which, when operated, places alternately the whole and a portion of the battery to line through the key K' and a conductor leading to a point, 2. From this point 2 two conductors, 3 and 4, lead, respectively, to the main line L and to an artificial line, L'. A differentially-wound receiving-instrument, R', has its respective coils included in the main line L and in the artificial line L'. This instrument is provided with a polarized

armature, and constructed in any convenient well-known manner as a polarized receiving instrument or relay.

The second or neutral receiving-instrument, R², is constructed with three sets of coils, b, b', and b². The coil b is included in the main-line circuit and the coil b² in the artificial line. The supplemental coil b' is included in an independent circuit, and is employed for maintaining the magnetism of the core of this receiving instrument during the reversals in the main-line current. This is accomplished by sending a momentary impulse through the coils b' at the moment of reversal. Such an impulse is derived from an inductorium or induction-coil, I. This coil is constructed in any convenient manner. For instance, it may be a closed magnetic ring or rectangular frame, i, having coils i¹ i² i³ i⁴ wound upon it. The coils i¹ i² are included, respectively, in the main line L and artificial line L'. The coils i³ and i⁴ are connected through the supplemental coil b' of the receiving-instrument R².

Variations in the strength of the current traversing the line will, it is evident, cause variations in the magnetism of the core, and thus induce currents in the coils i³ and i⁴. The effect of this induced current is to prevent the armature of the neutral relay from falling against the back-stop and remaining there long enough to give a false signal at the instant of the reversal of the current, caused by the operation of the pole-changing key, and this is done in the following manner: When a current in one direction is passing through the neutral relay it produces magnetism in the core of a certain polarity. When this current is reversed, the magnetism in the core of the neutral relay must first be discharged, and it then charges itself anew with the magnetism of a polarity due to the reversed current. Ordinarily this discharge and recharge occupy time enough for the armature to be drawn by its retractile spring to the back contact and give a false signal. Now, the effect of the induced current referred to is first to aid in the rapid discharge of the magnetism in the core of the neutral, and then immediately to aid in the rapid recharge of the cores with the mag-

netism due to the reversal of the current. Thus both operations are facilitated by the operation of the induced current and the time so shortened that the armature cannot reach the back contact, but is held practically without interruption to its front contact.

For the purpose of assisting the operation a condenser, C, may be connected across the terminals of the induction-coil, as shown, and the discharge from this condenser upon variations or reversals in the magnetism of the induction-coil will serve to send impulses of the proper character through the coil b' momentarily. There are several different ways in which the same general result may be accomplished, but one variation only will be described, since this will serve to fully illustrate the principle of the invention.

In Fig. 2 an arrangement as applied to a Wheatstone bridge is illustrated. One arm, w', of this bridge leads from the point 2 to the main line L, and the other arm, w², to the artificial line L'. Bridge-conductor w' includes the polarized relay R' and the neutral relay R², and also the primary of the induction-coil I. The secondary of this coil is connected through the supplemental coil b of the neutral relay in the same manner and with the same effect as was described with reference to Fig. 1.

Fig. 3 is a form of inductor which gives excellent results in practice. The coils intended for both the main and artificial lines have two each about seventy-five ohms resistance. The secondary coils have about seventy-five ohms resistance, respectively. When the coils are connected in series, a satisfactory induced current is obtained, and when connected up for practical operation, as already described with reference to Fig. 1, produces the effect of practically destroying all trace of false signals.

Instead of the separate inductor, as shown, a supplemental coil may be added to the polar relay, and this is connected with the supplemental coil of the neutral relay in the same manner as the secondary wire of the inductor. In this case the polar relay becomes the inductor and produces the same effect upon the neutral as the separate inductor already described. In this case a condenser may be placed between the supplemental coils in the same manner and with the same effect as described with reference to the separate induction and neutral relay. Considering the in-

ductor in Fig. 2 as being provided with a polarized armature and the instrument R' dispensed with, this organization would operate as described.

We claim as our invention—

1. The combination, with a polarized and neutral relay of a telegraph system and means for causing said instruments to respond to incoming and be silent to outgoing currents, of a supplemental coil applied to the neutral relay, an induction-coil having its primary wire connected in the main circuit and its secondary wire through said supplemental coil of the neutral relay, and a condenser having its respective plates connected to the terminals of the secondary coil.
2. The combination, with a polarized and a neutral relay, both of which are differentially wound, of a main and artificial line, respectively, including the opposing coils of said relays, an induction-coil having its primary wire included in the main and artificial lines, and a circuit for the secondary coil in which said supplemental coil is included, the connections being such as to cause the induced currents from the secondary coil to assist in the rapid discharge and recharge of the magnetism in the coils of the neutral relay at the instant of reversal.
3. The combination, with a main and artificial line, of a polarized and neutral relay, means for transmitting currents of alternating polarity and different strength upon said lines, and supplemental coils in said polarized and neutral relays, which supplemental coils are connected together.
4. The combination, with a main and artificial line, of a polarized and neutral relay, means for transmitting currents of alternating polarity and of different strength upon said lines, and supplemental coils in said polarized and neutral relays, which supplemental coils are connected together, and a condenser having its plates connected to the terminals of said supplemental coils.

In testimony whereof we have hereunto subscribed our names this 1st day of July, A. D. 1886.

JOHN M. MOFFATT.
EDWARD BLAKENEY.
